APPARATUS FOR THE MANUFACTURE OF
DENTURE MODELS

Max Fleischhacker, Tel Aviv, Israel

Application October 7, 1948, Serial No. 53,235
In Palestine October 27, 1947

3 Claims.

(Cl. 32—20)

2

a model of the edentulous maxillary jaw wherein the bottom face of the socle and the plane laid through the ridge representing the crest of the edentulous jaw include the same angle as the ear-nose plane and jaw crest in the head of the patient. On said cast the denture will then be modelled in wax or the like soft material, comprising a base plate and a rim.

The occlusal plane can now be reproduced on 10 the denture model parallel to the bottom face of the socle, and at a distance therefrom that is equal to the correct vertical dimension of the maxillary denture ascertained, as known per se, by reference to the length of the upper lip of 15 the patient. The upper face of the said wax rim is then so levelled and adjusted that it represents the occlusal plane. When thereafter the artificial teeth are anchored in the usual manner in the wax rim with their masticating surfaces flush 20 with the upper face of the rim, said masticating surfaces assume automatically their proper location in the occlusal plane.

Further objects and features of the invention 25 will become apparent from the following description in which the invention is set out in detail and by way of example only with reference to the accompanying drawings. In the latter:

Fig. 1 is a plan view of a facebow connected to an impression-tray;

30 Figs. 2 and 3 are respectively a fragmentary front view and fragmentary side elevation thereof;

Fig. 4 is a detail of the facebow on a larger scale;

35 Fig. 5 is a side elevation of the facebow in position on the head of the patient;

Fig. 6 shows the reversed facebow and tray placed on a table on which a plaster socle has been cast, the figure being a vertical section on line VI—VI of Fig. 7;

Fig. 7 is a plan view corresponding to Fig. 6;

Fig. 8 shows a detail of the plaster socle on a larger scale;

Fig. 9 is a perspective view showing the step 45 of reproducing the occlusal plane in the wax rim of the denture model on the plaster cast.

Turning first to Figs. 1 to 5, the apparatus according to this invention serving for locating the occlusal plane comprises a maxillary impression tray 1 of any known suitable design, provided with a tail 2 which, when the impression tray is inserted in the mouth, projects straight out therefrom. The tray is disconnectably articulated to the tray-holder of the facebow 50 unit comprising a yoke member 3. The articulation comprises a ball joint with two balls 3, 3' and sockets 6, 6'. The socket 6' is fixed to plate

1

This invention relates to the manufacture of dental prostheses, particularly to the proper location of the occlusal plane on and its reproduction in the prostheses.

The occlusal plane of the natural human denture is known to be parallel anteroposteriorly to the ear-nose plane, i. e. the plane laid through the arcuate line extending between the ears from tragus to tragus via the line of transition between upper lip and nose. Once the natural denture has been lost, the original occlusal plane is no longer recognizable and the dentist has first to find it again in the mouth of the patient and then to reproduce it in the artificial denture, failing which the latter will not be fitting and workable. For this purpose, quite a number of different devices and methods have been used so far, and while the location of the occlusal plane in the mouth of the patient can be done in various known ways with a fair measure of accuracy, the reproduction of this plane in the plaster-of-Paris casts on which the artificial dentures are modelled is neither easy nor secure.

It is the principal object of this invention to provide a method of, and means for, both locating the occlusal plane in the mouth of the patient and automatically reproducing it in the cast and denture model.

A further object of the invention is to provide a facebow adapted to be articulated to an impression tray inserted in the mouth of the patient, and to be adjusted in the ear-nose plane, and to be immobilized relative to the impression tray once it has been so adjusted.

A yet further object of the invention consists in providing such facebow with condyle marker attachments to allow determination of the distance of the denture from the condyles in the case of each particular patient.

The invention consists primarily in a method of manufacturing artificial maxillary dentures which comprises the steps of articulating a facebow to a maxillary impression tray inserted in the mouth of the patient, adjusting the facebow in the ear-nose plane, and fixing the facebow in its position relative to the impression tray, withdrawing from the patient the tray and facebow without altering their relative position; preparing a plaster-of-Paris socle on a casting table, casting plaster in the impression tray, and reversing the tray and facebow, placing the facebow with its normally upper side on said table, and at the same time the reversed tray on said socle, and allowing the plaster mass cast in the tray to combine with the socle.

When now the tray and facebow are removed after the cast has set and hardened, the cast is

7 secured to the yoke, while the socket 6 is secured to the tray-holder which comprises a clamp 4 provided with wing nut 5. The yoke is made of any suitable slightly elastic and flexible material, e. g. a metal such as brass, or a plastic material such as Celluloid. The tray is initially filled with a usual plastic impression mass and inserted in the mouth of the patient who bites thereon. Then the clamp 4 is fixed to the tail 2 and the facebow is closely applied to the face and adjusted in the ear-nose plane, as shown in Fig. 5. The ball joints are then immobilized by tightening clamping screws 11, 11'.

The facebow is also fitted at the ends of the yoke with condyle marker attachments. These comprise each a block 12 slidable on the yoke, and a clamping screw for immobilizing the block 12. A head 13 is provided with a holder pin inserted in a corresponding bore of the block 12 and adapted to be immobilized by means of a clamping screw, while a condyle pin 14 provided with a scale is slidable in the head 13 with friction. The blocks 12 and heads 13 are so adjusted that the pins 14 point towards the condyles, and slight pressure is exerted on pins 14 for making them contact the condyles.

The facebow and tray are now withdrawn from the patient without alteration of their relative positions.

Now, a thin plaster-of-Paris mix is cast in the impression made in the tray, and at the same time a socle 15 of a stiff plaster mix, still somewhat plastic, is prepared on a casting table or plate 9 (Fig. 6). The facebow and tray are turned upside down, the reversed facebow is laid on the table, and the tray with its plaster filling on the socle 15. The two plaster masses are now allowed to combine and set. The upper face of the cast reproduces the jaw with its crest while its bottom face includes with its upper face the same angle as the ear-nose plane does with the crest of the jaw. The bottom face of the socle can thus serve as a plane of reference for reproducing in the model the occlusal plane.

While the socle 15 is still in a plastic state, two crank axle pins 16, 16' are anchored therein. Their ends are formed by sleeves 17, 17'. The position of the axle pins is so adjusted that the sleeves 17, 17' receive the condyle pins 14 of the facebow in the positions given to the pins while the facebow had been applied to the head of the patient. The correct reproduction of these positions can be checked by means of the scale marked on the condyle pins. When the plaster cast is afterwards inserted in the articulator, the sleeves of said axle pins are slid on the axle of the articulator which brings the cast into the proper distance from the latter axle, i. e. at the same distance as the natural denture has from the condyles in the mouth of the particular patient.

A lug 18 is also anchored in the socle 15. Its underside is flush with that of the axle. The lug allows mounting the socle in a suitable tool for lifting it into the articulator without tilting, i. e. without disturbing the parallelity between the table surface and the bottom face of the socle.

When the plaster cast has set and hardened the denture model is prepared thereon. For this purpose, the vertical dimension of the denture is first ascertained by measuring the length of the upper lip of the patient in its middle and adding thereto 1 or 2 millimeters by which the edge of the median incisors will have to project be-

low edge of the upper lip. Then a conventional denture base 22 and rim 23 of wax or the like soft material are cast on the plaster cast. Now, the cutting implement shown in Fig. 9 is resorted to. This comprises a vertical standard 25 with foot 24 and a horizontal blade 26 secured by means of a clamping screw 19 in a holder 20 slidable on the standard 25. The blade 26 is adjusted at a height above the table corresponding to the vertical dimension of the denture ascertained as described above, and secured in this position by a screw 21. Then the wax rim is levelled by moving the cutting implement round the cast, or the cast against the cutting implement. During this operation the blade is not tilted in any direction. The plane of the cut surface is thus horizontal, i. e. parallel to the plane of the table which coincides with the bottom face of the socle 15. In other words, in a model in which the bottom face of the plaster cast represents the ear-nose plane of the patient, the top face of the wax rim represents the occlusal plane.

I claim:

1. A facebow for use in the manufacture of artificial dentures, comprising a yoke member adapted to be laid into the ear-nose plane of the patient, and an articulated attachment extending below the yoke member in the front part thereof, said attachment comprising a double ball joint and means for temporarily immobilizing the members of the double joint in the desired position of adjustment, and being adapted to detachably hold a maxillary impression tray at a variable angle and a variable distance relative to the plane of said yoke member.

2. A facebow for use in the manufacture of artificial dentures, comprising a yoke member adapted to be laid into the ear-nose plane of the patient, and an articulated attachment extending below the yoke member in the front part thereof, said attachment comprising a double ball joint and means for temporarily immobilizing the members of the double joint in the desired position of adjustment, and being adapted to detachably hold a maxillary impression tray at a variable angle and a variable distance relative to the plane of said yoke member; condyle pin holders located substantially at the ends of the yoke, an inwardly projecting condyle pin inserted in each condyle holder above the yoke member, and means for varying the height of the condyle pins above the yoke member.

3. A facebow unit for use in the manufacture of artificial dentures, comprising in combination a facebow as claimed in claim 2 with two crank-shaped pins having shorter ends adapted to be detachably secured to the inner ends of the condyle pins, and longer portions pointing towards the articulated attachment of the facebow.

MAX FLEISCHHACKER.
